UNITED STATES PATENT OFFICE.

EARL C. BUNNELL, OF STRATFORD, AND LESTER H. MESSINGER, JR., OF BRIDGEPORT, CONNECTICUT, ASSIGNORS TO THE C. C. JELLIFF MANUFACTURING CORPORATION, OF SOUTHPORT, CONNECTICUT, A CORPORATION OF CONNECTICUT.

LOOM WITH EDGE TRIMMERS.

Application filed April 5, 1926. Serial No. 99,867.

This invention relates to a loom especially adapted to the purpose of weaving wire fabric, usually heavy wire fabric, and having trimmers for removing end portions of the 5 cross-wires of the wire fabric.

An object of the invention is to provide a loom including a mechanically actuated beater or lay adapted to drive each woven cross-wire into its final position relatively 10 to the warp of the wire fabric being woven, and having novel and improved mechanism for automatically actuating the beater or lay.

A further object is to provide a loom for 15 weaving heavy wire fabric wherein the cross-wires are separately positioned in the sheds, usually by hand, and wherein said cross-wires are each automatically and mechanically driven into final position relatively to 20 the warp wires of a wire fabric or mesh being manufactured.

A further object is to provide a loom including a mechanically actuated beater or lay adapted to strike each woven cross- 25 wire two blows, the first blow to be a relatively heavy one forcing the cross-wire into the warp wires and crimping the warp wires, as will be understood, and the second blow to be a lighter one to make certain that 30 the cross-wire will be permanently and properly seated, the loom having mechanism for automatically actuating the beater or lay, the mechanism being adapted to cause the beater or lay to strike each cross-wire with 35 trip hammer blows.

A further object is to provide in the loom novel forms of cams for withdrawing the beater or lay and its reed away from a woven cross-wire, and a weight or weights for 40 actuating the beater or lay to cause it to strike a trip hammer blow against a woven cross-wire when released from a cam, whereby a blow or blows of any desired magnitude can be struck a cross-wire.

A further object is to provide in the loom 45 mechanism for automatically creating the sheds in synchronism with the operation of the beater or lay.

A further object is to provide in the loom 50 a feeding mechanism for the warp wires designed to automatically feed said warp wires ahead one step or stage for each cross-wire woven into the warp wires, whereby all of

the weaving can be accomplished at a single 55 location or station in the loom.

A further object is to provide a feeding mechanism for the warp wires as stated, which feeding mechanism will be adjustable to be capable of providing a one step or one 60 stage feed of any preferred length, the length in a particular case to depend upon the cross-sectional area of the wire being woven and the mesh of the wire fabric being produced.

A further object is to provide a power 65 operated loom which is produced by conversion of a well known type of hand operated loom for weaving heavy wire fabric.

A further object is to provide a loom for 70 weaving wire which can consist mostly of standard or commercial parts, this being especially so with respect to the driving mechanism of the loom.

And a further object is to provide in the 75 loom unique mechanism for trimming the edges of the woven fabric; that is to say, to provide edge trimmers adapted to remove the ends of the weft or cross-wires preferably at the location of the outermost of the warp wires.

With the above objects in view, as well as 80 others which will appear as the specification proceeds, the invention comprises the construction, arrangement, and combination of parts as now to be fully described and as hereinafter to be specifically claimed, it being understood that the disclosure herein is 85 merely illustrative and intended in no way in a limiting sense, changes in details of construction and arrangement of parts being permissible so long as within the spirit 90 of the invention and the scope of the appended claims.

In the accompanying drawings forming a part of this specification.

Fig. 1 is an elevational view of the drive 95 side of a loom having the features of the invention;

Fig. 2 is a front elevational view thereof;

Fig. 3 is an enlarged fragmentary elevational view of the side of the loom opposite 100 the drive side;

Fig. 4 is an enlarged fragmentary sectional view, on line 4-4 in Fig. 2;

Fig. 5 is a fragmentary elevational view of the drive, disclosing the side thereof opposite that shown in Fig. 2;

Fig. 6 is a detail sectional view of a feature of the warp wire feeding mechanism, on line 6—6 in Fig. 2;

Fig. 7 is a detail sectional view of another feature of the warp wire feeding mechanism, on line 7—7 in Fig. 3;

Fig. 8 is an enlarged sectional view detailing the edge trimmer, on line 8—8 in Fig. 3; and

10 Fig. 9 is an enlarged fragmentary elevational view partially in section, of the edge trimmer as seen from the right in Fig. 8.

With respect to the drawings, 10 denotes the frame of the loom, 11 the breast beam, 15 12 the back beam, 13 the warp wires upon the breast beam and back beam, the ends of the warp wires being secured together, as at 14, whereby during the weaving operation each warp wire is a continuous wire 20 about the breast beam and back beam, as will be clear from Figs. 1, 3 and 4. 15 is a warp wire tensioning rack having the back beam 12, 16 is an adjusting screw for said rack, 17 are spaced apart notches in 25 said rack for the shaft 18 of the back beam, and 19 are notches in the frame 10 for the shaft 20 of the breast beam 11. The upper part of the frame 10 has brackets 21 supporting a cross-rod 22 upon which arms 23 30 of a beater or lay 24 are pivotally suspended, 25 representing the reed of said beater or lay having dents 26. 27 represents the harnesses of the loom which ride on overhead pulleys 28 and have heddles 29 35 through which the warp wires 13 are threaded, and 30 are the treadles for operating the harnesses.

The parts so far described are all common to a type of hand operated loom for weaving wire fabric therefore well known. 40 In the operation of said hand loom, the harnesses are actuated by foot to produce the sheds, the cross-wires are inserted, usually by hand, and the beater or lay is manually 45 operated to strike several blows against each cross-wire to be woven, usually a relatively heavy one forcing the cross-wire into the warp wires and crimping the warp wires, and a lighter blow to make certain that the 50 cross-wire is permanently and properly seated.

When using the loom of the present invention, the cross-wires may be, and preferably are, positioned in the sheds by hand, 55 but the harnesses for producing the sheds are power actuated, as is also the beater or lay to strike the blows, desirably two blows for each cross-wire, driving the cross-wires home and insuring their permanently set positions with respect to the warp wires.

Of the mechanism for actuating the harnesses 27 and the beater or lay 24, 31 is a main shaft in brackets 32 and having a loose pulley 33 adapted to be driven from any 60 source of power as by a belt (not shown)

over the pulley, 34 denoting a friction clutch fixed to the main shaft 31 and adapted to engage said pulley to cause it to rotate said main shaft 31.

A pinion 35 fixed upon the main shaft 31 70 meshes with a large gear 36 fixed upon a beater-actuating cam shaft 37 having its opposite ends 38 mounted in the frame 10 as at 39. The cam shaft 37 has upon each of its opposite end portions, preferably within the 75 side members of the frame, a large cam 40 and a small cam 41, said cams 40 and 41 desirably having external surfaces, denoted 42 and 43, respectively, which extend spirally outwardly from adjacent the axis of 80 the beater-actuating cam shaft 37, each cam 40 and 41 terminating abruptly at its outer end, as represented at 44 and 45, respectively. See Fig. 4.

Levers 46 pivoted at 47 upon brackets 48, 85 one upon each side member of the frame, are connected by links 49 with a cross-shaft 50 of the beater or lay 24, each lever 46 having a roller 51 adapted to ride once upon the external surfaces of cams 40 and 41 90 during each complete revolution of the beater-actuating shaft 37. The cams 40 and 41 are adapted to swing the beater or lay arms 23 rearwardly to oblique position, as disclosed in Fig. 1, the cams 40 swinging 95 said beater or lay arms 23 a considerable distance away from the vertical, and the cams 41 swinging said beater or lay arms a less distance. When the cams 40 and 41 release said beater or lay it is adapted to 100 swing as a pendulum to cause the dents 26 of the reed of the beater or lay to strike against a cross-wire previously positioned, as by hand, in the shed 52. Weights 53 upon cords 54 riding over idler pulleys 55 105 upon the frame and secured to the beater or lay 24 or its cross-shaft may assist in causing the beater or lay to strike its blow, or the weights 53 may alone constitute the 110 actuating means for causing the beater or lay to strike the cross-wires, as will be obvious. Clearly, the cams 40 and 41 can be constructed to give the beater or lay any working stroke desired, and the weights 53 can be heavy or light to cause blows of any 115 desired magnitude to be struck. All of the blows upon the cross-wires will be clear and sharp; in fact, the blows will all be trip hammer blows.

The beater-actuating shaft has a sprocket 120 56 fixed upon it, the sprocket carrying a sprocket chain 57 also riding upon a sprocket 58 fixed upon a harness-actuating cam shaft 59 mounted in the side members of the frame at 60. 61 are cams upon the harness-actuating cam shaft 59 adapted to engage and actuate the harnesses 27, said cams 61 being adapted to engage rollers 62 upon the treadles 30. See Figs. 1 to 4. The harness-actuating cam shaft is related to the 125 130

beater-actuating cam shaft in such manner that for each complete rotation of the beater-actuating cam shaft there is a rotation of the harness-actuating cam shaft one hundred and 5 eighty degrees, so that each cam 40 and 41 will allow a blow to be struck an inserted cross-wire for each shed produced, with front harness up and back harness down, and vice versa. That is to say, during each revolution or complete cycle of the beater-actuating shaft, the harness-actuating shaft rotates a half revolution or half-cycle, producing one shed, so that each cam 40 causes the beater or lay to be actuated and released to 10 strike a heavy blow against a cross-wire, and each cam 41 causes the beater or lay to be actuated and released to strike a lighter blow against said cross-wire, all while a shed is existent. At the completion of the lighter 15 blow, a new shed is caused to be formed by the harness-actuating cams, one being up while the other is down, a new cross-wire is inserted, and the cycle of operations is 20 repeated. Preferably the cross-wires are crimped or bent before insertion in the sheds, 25 as is the usual practice.

There is in the loom a feeding mechanism for the warp wires to feed said wires ahead one step or stage for each cross-wire woven 30 into the warp wires, so that all of the weaving can be advantageously accomplished at a single location or station in the loom, and the warp wire feeding mechanism is capable of adjustment to provide a one step or one 35 stage feed of any preferred length, the length to depend upon the cross-sectional area of the wire being woven and the mesh of the fabric being produced.

Of the warp wire feeding mechanism, 63 40 is a lever secured at 64 to a drum 65 about a ratchet 66 fixed to the shaft 20 of the breast beam 11 as by a key 67, 68 denoting rollers upon the perimeter of the ratchet and engaging the drum. The perimeter of 45 the ratchet is so constructed that the drum 65 is freely rotatable in one direction (in the direction of the arrow in Fig. 6), but the instant attempt is made to rotate said drum in opposite direction (in clockwise 50 direction in Fig. 6), the rollers 68 lock the ratchet and drum to each other to cause the shaft 20 and the breast beam to be rotated. 55 69 is a link pivoted at 70 to the lower end of the lever 63 and at 71 upon a device 72 fixed upon the beater-actuating cam shaft 37, the pivot 71 being adjustable in any convenient manner from and toward the axis of said shaft 37. A suitable arrangement is disclosed in Figs. 3 and 7. In said figures, 73 60 is a shouldered block slidable in a radial slot 74 in the device 72, and 75 is an adjusting screw in the device 72 for said block 73. 76 is a threaded stud upon said block which enters an opening 77 in the end of the link 65 69 spaced from the lever 63, 78 indicating a

bushing upon said stud and between the link 69 and the device 72. 79 is a nut upon the thread of the stud 76, and 80 is a washer upon the stud and between the nut and link 69. Clearly, by use of the adjusting screw 75 75, the stud 76 can be set at desired distance from the axis of the shaft 37.

Evidently, the distance the pivot 71 is spaced from the axis of the shaft 37 determines the extent of movement of the link 69 and the lever 63. A complete rotation of the shaft 37, together with the device 72, causes the lever 63 to oscillate back and forth once, movement in one direction rotating the shaft 20 of the breast beam 11, and movement in opposite direction causing the drum 65 to rotate free of the ratchet 66, as will be obvious. Forward movement of the lever 63, as disclosed, rotates the breast beam one 80 step or one mesh in the feeding direction of the warp wires, the length of each rotation depending upon the position of the pivot 71 relatively to the axis of the shaft 37, and determining the length of each feeding movement of the warp wires. The feed will 85 be so adjusted that all of the weaving can be accomplished at approximately the same location or station in the loom, and the length of each feeding movement will depend upon the mesh of the wire fabric being produced. 90

The cross-wires woven into the warp wires are longer than the distance representing the width of the finished wire fabric to protrude at both sides of the fabric beyond the outermost of said warp wires to make certain that all of the cross-wires will extend the width of the fabric, as will be understood. Mechanism is provided in the loom for removing the ends of said woven cross-wires, preferably at the location of the outermost of the warp wires. 100

This mechanism is best disclosed in Figs. 1, 3, 4, 8, and 9. In said figures, 81 are brackets secured upon the side members of the frame 10 and supporting two shafts extending transversely across the frame, including a rotatable forward shaft 82 and a fixed rearward shaft 83. These shafts carry two edge trimmers, one at each side of the frame within the side members. Of each edge trimmer, 84 is a supporting member for the relatively stationary knife of the trimmer, said member 84 being mounted upon the shaft 82, as at 85, and upon the shaft 83, as at 86, to be adjustable longitudinally of said shafts. 87 is a set screw in the member 84 adapted to engage the shaft 83 to fix the trimmer upon the shaft when adjusted to desired position along the length of the shafts. The supporting member 84 carries a vertically adjustable knife 88, 89 representing horizontal holding screws in elongated slots 90 in said knife 88 and entering the supporting member 84, and 91 indicating vertical adjusting screws in said 110 115 120 125 130

member 84 and engaging the upper face 92 of the knife opposite its cutting edge 93. 94 is a supporting member for the movable knife of the trimmer, said member 94 being pivoted at 95 upon the supporting member 84. 96 is a vertical knife upon the member 94, 97 indicating horizontal holding screws in elongated slots 98 in the member 94 and entering the knife 96. 99 is an eccentric or cam upon the shaft 82 beneath and in engagement with the movable supporting member 94, 100 representing a key of said eccentric or cam which is slidable in a key-way 101 of said shaft 82, the key rendering the eccentric or cam rotatable with the shaft. 102 is a cap fixed to the stationary supporting member 84 as at 103, the cap being close to or contiguous with adjacent faces of the pivoted supporting member 94 and the eccentric or cam 99, whereby the cap locates the member 94 and eccentric or cam 99 relatively to each other and relatively to the member 84. That is to say, the member 94 and the eccentric or cam 99 are between the member 84 and the cap 102 secured to said member 84, so that when the member 84 is moved along the shafts 82 and 83, the member 94 and the eccentric or cam 99 move with said member 84, the cap 102 and member 84 insuring the relation of the member 94 and the eccentric or cam relatively to each other.

Numeral 104 indicates levers, one fixed to each end of the shaft 82, as at 105, beyond the side members of the frame, and 106 denotes retainers, one upon the upper end of each lever 104, which receive the cross-shaft 50 of the beater or lay 24, the body of each retainer 106 being spaced from a lever 104 a distance about equal to the diameter of the cross-shaft 50 and the length of said body being greater, whereby oscillatory movements of the beater or lay cross-shaft will be imparted to the levers 104, and said cross-shaft can have movement in the retainers 106 longitudinally of the levers 104 during said oscillatory movements.

Clearly, oscillatory movements imparted to said levers 104 by actuations of the beater or lay, through said cross-shaft 50, will oscillate the eccentrics or cams 99 and thus cause the pivoted supporting members 94 to oscillate, moving the knives 96 relatively to the knives 88, said knives being set with respect to each other to together cut off the ends of the cross-wires, as will be apparent from Fig. 8, 107 indicating the cutting edge of each knife 96. L-shaped arms 108, one for each edge trimmer, secured at 109 upon the outer ends of the members 94, are fit as at 110 beneath the eccentrics or cams 99 to insure that said members 94 will follow the movements of said eccentrics or cams. In practice, the edge trimmers are adjusted longitudinally of the shafts 82 and 83 to the positions desired, depending upon the

width of the wire fabric to be woven, to cut off the ends of the cross-wires just outside of the outermost of the warp wires.

It will be apparent that the present power operated loom was produced by conversion of a type of hand operated loom for weaving heavy wire fabric, and that the parts incorporated in the hand operated loom to produce the power operated loom are, for the most part, commercial or standard, this being especially so with respect to the driving mechanism of the loom.

Having thus fully described the invention, what we claim as new and desire to secure by Letters Patent is:

1. A loom for weaving wire fabric, comprising a beater, means for actuating the beater to cause it to strike a plurality of blows against each of cross-wires to be woven into warp wires, said means comprising a plurality of cams for withdrawing said beater from the weaving location, there being a cam for each blow to be struck a cross-wire, and each cam being adapted to release said beater when withdrawn, and means upon said beater for causing it to strike a trip hammer blow against a cross-wire each time it is released from a cam, said last mentioned means comprising a weight, a cord suspending said weight from said beater, and a rotatable member over which said cord passes.

2. A loom for weaving wire fabric, comprising a beater, means for actuating the beater to cause it to strike a plurality of blows against each of cross-wires to be woven into warp wires, said means comprising a plurality of cams for withdrawing said beater from the weaving location, there being a cam for each blow to be struck a cross-wire, and each cam being adapted to release said beater when withdrawn, means upon said beater for causing it to strike a blow against a cross-wire each time it is released from a cam, and means actuated by the beater actuating means adapted to cut off the ends of cross-wires of the woven wire fabric at locations in advance of said beater.

3. A loom for weaving wire fabric, comprising a beater, actuating means for withdrawing said beater from the weaving location and for releasing said beater to cause it to strike a plurality of blows against each of cross-wires to be woven into warp wires, and means actuated by the beater actuating means adapted to cut off the ends of cross-wires of the woven wire fabric, said last mentioned means being actuated each time said beater strikes a blow against a cross-wire, whereby the cross-wire cut-off means is actuated more than once during the period in which any one cross-wire is at the cutting off location.

4. A loom for weaving wire fabric, com-

prising a beater, means for actuating the beater to cause it to strike a plurality of blows against each of cross wires to be woven into warp wires, said means comprising a plurality of cams for withdrawing said beater from the weaving location, there being a cam for each blow to be struck a cross-wire, and each cam being adapted to release said beater when withdrawn, means 10 for causing said beater to strike a blow against a cross-wire each time it is released from a cam, and cross-wire cut-off means actuated by the beater actuating means, said cross-wire cut-off means functioning once 15 for each blow struck by said beater.

5. A loom for weaving wire fabric, comprising a beater, actuating means for withdrawing said beater from the weaving location and for releasing said beater to cause 20 it to strike a plurality of blows against each of cross-wires to be woven into warp wires, feeding mechanism for the warp wires adapted to feed said warp wires ahead one mesh for each cross-wire woven into 25 the warp wires, and means actuated by the beater actuating means adapted to cut off the ends of cross-wires of the woven wire fabric as fed by said feeding mechanism past said beater and to said cut-off means, 30 said last mentioned means being actuated each time said beater strikes a blow against a cross-wire.

6. A loom for weaving wire fabric comprising a beater, means for actuating the beater to cause it to strike a plurality of blows against each of cross-wires to be woven into warp wires, said means comprising a plurality of cams for withdrawing said beater from the weaving location, there being 40 a cam for each blow to be struck a cross-wire, and each cam being adapted to release said beater when withdrawn, means for causing said beater to strike a blow against a cross-wire each time it is released from a cam, feeding mechanism for the warp wires adapted to feed said warp wires ahead one 45 mesh for each cross-wire woven into the warp wires, and cross-wire cut-off means actuated by the beater actuating means, both 50 said cross-wire cut-off means and said warp wire feeding mechanism functioning once for each stroke of said beater.

7. A loom for weaving wire fabric, comprising a beater, means for actuating said beater to incorporate cross-wires into warp wires of a wire fabric being woven, and means actuated by the beater actuating means for cutting off the ends of each cross-wire at location spaced from said beater, 55 said last mentioned means comprising cut-off knives, a lever associated with one of said knives, a cross-shaft upon the beater, and a retainer upon said lever and about said cross-shaft, said lever extending downwardly from said cross-shaft, and said retainer

permitting relative longitudinal movement between said lever and said beater.

8. A loom for weaving wire fabric, comprising a beater, means for automatically actuating the beater to incorporate cross-wires into warp wires of a wire fabric being woven, said beater including a horizontal cross-shaft, and means actuated by the beater actuating means for cutting off the ends of each cross-wire, said last mentioned means comprising knives, a lever associated with one of said knives and extending downwardly from said beater, and a retainer upon said lever and about said cross-shaft, said retainer permitting relative oscillatory 75 and longitudinal movement between said lever and said beater.

9. A loom for weaving wire fabric, comprising a beater, means for automatically actuating the beater to incorporate cross-wires into warp wires of a wire fabric being woven, and means for cutting off the ends of the cross-wires as woven into the warp wires of the wire fabric, said cutting off means being actuated from said beater and comprising a lever oscillatably associated with said beater and extending downwardly from and at an angle to said beater, a shaft supporting said lever, an eccentric upon said shaft, a movable knife associated with said eccentric, and a fixed knife with which said movable knife cooperates.

10. A loom for weaving wire fabric, comprising a beater, a breast beam, a back beam, said beams being adapted to receive warp wires of a wire fabric to be woven and the ends of the warp wires being adapted to be secured together to constitute a continuous belt about said breast beam and back beam, means for actuating the beater to incorporate cross-wires into warp wires of the wire fabric, feeding mechanism for the warp wires, and means actuated by the beater actuating means for cutting off the ends of each cross-wire at a location below a plane passing through the axes of said breast beam and back beam and at the side of said beams opposite the location where said cross-wires are incorporated in said warp wires.

11. A loom for weaving wire fabric, comprising a beater, a breast beam, a back beam, said beams being adapted to receive warp wires of a wire fabric to be woven and the ends of the warp wires being adapted to be secured together to constitute a continuous belt about said breast beam and back beam, means for actuating the beater to incorporate cross-wires into warp wires of the wire fabric, feeding mechanism for the warp wires adapted to feed said warp wires ahead one mesh for each cross-wire woven into the warp wires, and means actuated by the beater actuating means for cutting off the ends of each cross-wire at the side of said breast beam and back beam opposite the location

where said cross-wires are incorporated in said warp wires, said cutting off means comprising a lever pivotally associated with said beater and extending downwardly therefrom, 5 a movable knife with which said lever is associated, and a fixed knife with which said movable knife cooperates.

12. A loom for weaving wire fabric, comprising a breast beam, a back beam, a beater, 10 means for actuating the beater comprising a drive shaft, a cam rotated by said drive shaft, levers associated with said cam to withdraw said beater from the weaving location and release the beater whereby it can 15 strike a blow against a cross-wire to be woven into warp wires, a device actuated from said drive shaft, lever connections between said device and one of said beams for advancing said warp wires one mesh for 20 each cross-wire woven into the warp wires, a second lever pivotally associated with said beater and extending downwardly therefrom, and means for cutting off the ends of 25 said cross-wires associated with said second lever.

13. A loom for weaving wire fabric, comprising a beater, means for actuating the beater to incorporate cross-wires into warp wires of a wire fabric being woven, and 20 means actuated by the beater actuating means for cutting off the ends of the woven cross-wires, said last mentioned means comprising a unit including a relatively stationary supporting member having a knife,

35 spaced apart shafts supporting said member, one of said shafts being capable of rotation, a relatively movable member having a knife, a lever for actuating said rotatable shaft, said lever being pivoted to said beater, and an eccentric associated with said rotatable shaft for actuating said movable member relatively to 40 said fixed member.

14. A loom for weaving wire fabric, comprising a beater, means for actuating the beater to incorporate cross-wires into warp wires of a wire fabric being woven, and 45 means actuated by the beater actuating means for cutting off the ends of the woven cross-wires, said last mentioned means including a relatively stationary member having a knife, spaced apart shafts supporting said member, one of said shafts being capable of rotation, a relatively movable member having a knife, a lever for actuating said rotatable shaft, said lever being pivoted to said beater, an eccentric associated with said rotatable shaft for actuating 50 said movable member relatively to said fixed member, and means insuring that said movable member will follow the movements of 55 said eccentric.

Signed at Bridgeport, in the county of Fairfield, and State of Connecticut, this 3rd day of April, A. D., 1926.

EARL C. BUNNELL.
LESTER H. MESSINGER, JR.
